GEORGE W. CASILEAR, OF WASHINGTON, DISTRICT OF COLUMBIA.

Letters Patent No. 84,341, dated November 24, 1868.

METHOD OF PREVENTING THE ALTERATION OF NUMBERS ON BONDS, &c.

The Schedule referred to in these Letters Patent and making part of the same.

To all whom it may concern:

Be it known that I, GEORGE W. CASILEAR, of Washington, District of Columbia, have invented a new and improved Mode of Preventing the Alteration of Numbers or the Addition of Figures on Bonds, Notes, and other Securities; and I do hereby declare that the following is a full and exact description thereof, reference being had to the accompanying engravings.

The nature of my invention consists in printing the numbers on bonds, notes, or other securities, (as shown at A in the accompanying engraving,) in brackets, or other peculiar forms, leaving no room for adding an additional number on either side of the figure or figures composing the number; and in order to prevent the alteration of the numbers, or the removal of the

parentheses or other marks, I propose to print the whole on a finely-engraved background, B, of scroll-lattice work, or any other printed matter; the ground-work of which shall be printed in fugitive colors or inks.

What I claim as my invention, and desire to secure by Letters Patent, is—

Printing numbers in parentheses, or between any other marks or forms, on a fugitive ground or background, tint, or color, thus effectually preventing alteration of the figures or numbers, as substantially set forth.

GEO. W. CASILEAR.

Witnesses:

HENRY J. HUNTER,
F. A. CASILEAR.
